GAS ANALYSIS APPARATUS

Application filed August 19, 1926. Serial No. 130,216.

The general object of my present invention is to provide improvements in apparatus for determining the composition of a gas by measuring or comparing electrical quantities which are dependent on the thermal conductivity of the gas, which depends in turn upon the composition of the gas. My improved apparatus is like that heretofore known for the purpose in that it comprises a structure or housing containing cells in each of which is located a resistor, the resistance of which varies with the temperature of the resistor, and in that the temperature of each such resistor depends upon the heating effect of an electric current passing through it and upon the cooling effect of a body of gas filling the cell and conducting heat from the heated resistor to the surrounding wall of the cell. Usually such apparatus comprises at least one cell in which the corresponding resistor is surrounded by the gas to be analyzed and at least one other cell, the resistor in which is surrounded by a standard or comparison gas, which frequently is air, so that the composition of the gas to be analyzed is determined by a comparison of the resistance values of the different resistors which are ordinarily connected into a Wheatstone bridge. My present invention comprises improvements in the cell containing structures which facilitate the proper construction of such structures at a relatively low cost of production. The invention also comprises improvements in the mode of mounting the resistors in the gas cells which are desirable from a mechanical standpoint, and which permit of a novel adjustment of the resistors to vary the temperatures attained by them under given conditions, thereby facilitating the calibration of the apparatus. The improved cell containing structure is characterized particularly by the fact that the cell walls are so formed as to resist the corrosive action of gases having a corrosive action on metals such as iron or brass heretofore employed, and so as to prevent objectionable gas diffusion through the cell wall pores such as sometimes occurs when the cell walls are formed of iron or brass,

The invention is further characterized by the provisions for regulating the temperature and moisture content of the gases being compared, and in particular by the provisions made for having the gases compared practically saturated with water vapor while, at the same time avoiding the presence of entrained moisture in the gases flowing through the comparison cells.

In a preferred form of construction, the necessary means for preliminarily cooling the gases and condensing excess moisture and filtering the gases to clean them, preparatory to their admission to the comparison cells are combined in a unitary mechanical structure with the comparison cells, instead of being separate from the comparison cell structure, as has heretofore been the practice. By this combination the construction of gas analysis apparatus is simplified and cheapened, the apparatus is made more compact, and the maintenance of practically the same temperature and humidity conditions for the gases compared is facilitated.

The various features of novelty which characterize my invention are pointed out with particularity in the claims annexed to and forming a part of this specification. For a better understanding of the invention, however, its advantages and specific objects attained by it, reference should be had to the accompanying drawings and descriptive matter in which I have illustrated and described preferred embodiments of the invention.

Of the drawings:

Fig. 1 is a plan view of a gas analysis device;

Fig. 2 is a section on the broken line 2—2 of Fig. 1;

Fig. 3 is a section on the line 3—3 of Fig. 1;

Fig. 4 is a partial section on the line 4—4 of Fig. 1;

Fig. 5 is a section on the line 5—5 of Fig. 3;

Fig. 6 is a diagrammatic representation of apparatus for measuring the CO and CO₂ content of flue gases;

Fig. 7 is a section on the line 7—7 of Fig. 1.

8 illustrating a modified construction; Fig. 8 is a section on the line 8—8 of Fig. 7; and

5 Fig. 9 is a diagram of circuit connections which may be employed with the apparatus shown in Fig. 6.

In Fig. 6 I have diagrammatically illustrated the use of various features of the present invention in apparatus comprising 10 a sampling tube A adapted to be inserted into a furnace chamber or flue from which furnace gases are to be withdrawn for analysis. A portion of the gases thus withdrawn from the sampling tube A passes 15 through a pipe B to the gas inlet of a device C containing provisions for cooling and cleaning the gases, and containing comparison cells for determining the CO_2 content of the gases. The gases entering the device 20 C, pass from the latter through a pipe B to a device CA containing comparison cells for determining the CO content of the gases withdrawn through the sampling tube A. The device CA also contains provisions for 25 cooling and cleaning gas coming from the sampling tube A through the pipe B². Interposed in the pipe B² between the sampling tube and device CA, is a furnace F containing 30 copper oxide or an analogous oxidizing agent for converting the CO content of the gases passing through the furnace into CO_2 . The gases entering the device CA through the pipes B' and B², are withdrawn from 35 the device CA through a pipe B³ running to the inlet of an aspirator G in which water supplied under pressure through the pipe L³ creates the draft for causing the above described flow through the apparatus. G' represents the outlet from the aspirator 40 through which the air, gas and aspirating water are discharged.

As shown, the aspirating water is supplied from a pipe L and is utilized in cooling the gases in the devices C and CA. For 45 this purpose branch L' runs from the supply pipe L to the water inlet of each of the devices C and CA. The water outlet of each of the devices C and CA is connected by a corresponding pipe L² to the pipe L³.

50 The device C comprises a metallic body D and a metallic cell block E extending into the upper end of, and nearly, but not quite filling a cavity D' in the member D. The cell block E is formed with a lateral flange 55 or head E' at its upper end resting against, and bolted to the top of the member D. The body D and cell block E may each be a one-piece aluminum casting. The body is formed with vertical water channels D² in 60 communication at their upper ends and connected at their lower ends, one to the inlet pipe L', and the other to the outlet pipe L² pertaining to the device.

65 The gas supplied to the device C by the pipe B passes successively up, then down,

and then up, through connected vertical passages D³, D⁴, and D⁵, formed in the body D, to a gas inlet passage E⁴ formed in the head or lateral flange E' of the cell block E. In flowing through the passages D³, D⁴, and D⁵, the gas is cooled and cleaned. The gas is subjected to a cleaning action in each passage, but the gas is cooled, wholly or mainly, in the passage D³ which is in relatively good heat transfer relation with the water passages D², and serves in lieu of the separate condenser heretofore employed to condense excess moisture in the flue gases. To clean the gas, as well as to screen out entrained water of condensation, suitable screening or filter material is placed in the passages, such as glass beads d, glass wool d', steel wool d², absorbent cotton d³, and an alundum filter tube d⁴. The latter as shown is carried by a plug E² threaded through an opening in the cell block head E' and formed with passages through which the interior of the tube d⁴ communicates with the channel E⁴. D⁶ is a window through which the interior of the passage D⁵ may be inspected.

Formed in the body of the cell block E are two vertical resistance containing cells e, two vertical resistance containing cells ea, and a vertical chamber e'. The cells e and ea and chamber e' may be holes formed by a 95 drill entering the cell block at its upper end. The open upper ends of each of the cells e and ea are closed by a plug M and threaded gland M' securing the plug in place; and a plug m closes the upper end of the chamber 100 e'.

The cells e communicate at their upper ends with, and receive gas from the channel E⁴, and discharge the gas through restricted outlets at their lower ends into the temperature equalizing space within the cavity D' surrounding and beneath the cell block. This space also receives some gas at its upper end directly from the channel E⁴ through parts E³. The gas outlet pipe B' 110 leads from the bottom of the cavity D'. The cells ea communicate with the chamber e' at their upper ends and with the latter are sealed and contain air or other standard or comparison gas. The chamber e' contains 115 a humidity regulating agent which might be a drying agent, but preferably is water wet cotton or some other humidifying agent.

The plugs M closing the upper ends of the cells e and ea are formed of insulating material and support the cell resistance terminals O and P. As shown, each plug M is formed with a central passage for a barlike terminal O which extends through the plug, and secured in any desired axial adjustment 125 therein by a set screw O'. The terminal bar O in each cell e has its lower end secured to the upper end of a corresponding resistance R, which is in the form of a helix and has its lower end connected to a terminal P 130

shown as a metal rod extending through and secured in the corresponding plug M. As shown, the lower end of each terminal P carries a spider P' of insulating material for centering the lower end of the resistance in the corresponding cell without closing the latter. The terminal bars O extending into the upper ends of the cells ea have their lower ends connected to the upper ends of helical resistances r which have their lower ends supported by arms P and spiders P' just as do the resistances R.

In the preferred construction illustrated, a so-called Wheatstone bridge balancing resistance in the form of a slide wire S, is mounted on the periphery of a semicylindrical block of bakelite or other insulating material S' secured to the head of the member E. The block S' has journalled in it a shaft S² carrying a brush S³ which bears against the resistance S at a point depending on the angular position of the shaft S². The block S' may also serve as a support for binding posts or the like through which the resistors R and r are connected to the terminal leads or conductors of the device C which, as shown, are incorporated in a cable Q advantageously extending through a vertical channel D' formed in the housing body.

The device CA may be identical in construction with the device C except that as shown in the device CA the chamber e' does not serve as a drying chamber but as a means for connecting the gas pipe B' to the tops of the cells ea, and that the latter are connected at their lower ends by restricted ports to the space in the cavity D' beneath the cell block E. The gas with its original CO content converted into CO₂ in the furnace F, conveyed by the pipe B² to the device CA, after passing through the cooling and cleaning passage of the device CA enters the cells e of the latter. The gas outlet pipe B³ leads from the bottom of the cavity D' of the device CA.

In Fig. 9 I have illustrated diagrammatically one form of circuit arrangements by which the resistances R and r of the devices C and CA may advantageously be employed in connection with a single meter K to exhibit in a readily comparable manner the CO, and CO₂ contents of the gases drawn into the apparatus through the sampling tube A. In Fig. 9 the two resistances R of the device C form opposing arms of a Wheatstone bridge, of which the other two arms are formed by the resistances r. The bridge is energized by a source of current as a battery U, conductors 1 and 2 connecting the battery to opposing junction points of the bridge. As shown, the conductor 2 is connected to the slide wire brush S³ which forms one junction of the bridge, the slide wire resistance S connecting adjacent ends

of one resistance R and one resistance r. U' represents an ammeter for measuring the bridge energizing current, and U² an adjustable resistance in the conductor 2 by which the strength of the bridge current can be regulated. The other two junction points of the bridge of the device C are connected by conductors 3 and 4 to terminals of a switch 1.

The resistors R and r of the device CA are connected into a Wheatstone bridge arranged, energized and connected to terminals of the switch I as is the bridge of the device C. The connections to the bridge of the device CA comprise conductors 10, 20, 30, and 40 corresponding to the conductors 1, 2, 3, and 4, respectively, associated with the bridge of the device C. The switch I is intended for manual or automatic actuation to separately connect the two bridges in regular alternation to the winding of an indicating or recording galvanometer K. Advantageously, though not necessarily, the pointer K' of the meter K swings over the meter scale K² in one direction from the zero point K³ of the scale when connected by conductors 3 and 4 to the bridge C to thereby indicate the CO₂ content of the gas, and swings in the opposite direction from the zero point to indicate the CO content of the gas when the meter is connected through conductors 30 and 40 to the bridge of the device CA.

With the meter pointer thus swinging in opposite directions from the zero point of the instrument to indicate CO₂ and CO contents, respectively, the zero point is preferably located at one side of the center of the scale so that the instrument will give a wider range of scale readings when measuring CO₂ than when measuring CO, which is desirable in view of the fact that the CO₂ variations will normally require a wider range of movement of the pointer for their proper indication than will the CO measurements. With the arrangement for this purpose shown in Fig. 9, the portion of the scale K² at the right of the zero point K³ will ordinarily be graduated in CO percentage units, while the portion of the scale at the left of the zero point will be graduated in CO₂ percentage units. When, as will be usually the case, the meter K is a recording meter, the location of the CO and CO₂ records at opposite sides of the zero line makes it unnecessary to have the two records made in different colors, though of course, they may be colored differently, but records in two colors will ordinarily be desirable, though not essential, if the instrument is arranged to have its pointer swing in the same direction from zero in making the CO and CO₂ records. Except as it may be desirable to have the above mentioned specially formed

scale, the meter K and the switch I may be of known type.

As those skilled in the art will understand, when the instrument K is connected by the conductors 3 and 4 to the Wheatstone bridge of the device C and the bridge is properly energized and calibrated so that the pointer K will stand at the zero point when the resistors R and r are at the same temperature, the lower thermal conductivity of the CO_2 content of the gases in the cells e as compared with the air in the cells ea , will cause the resistors R to be hotter, and in consequence to have higher resistances than the resistors r by an amount which is dependent on the amount of CO_2 in the gases passing through the cells e . Similarly, when the bridge of the device CA is connected to the winding of the meter K, the instrument pointer K' will be deflected more or less according to the excess in the CO_2 content of the gases passing through the cells ea , over the CO_2 content of the gases passing through the cells e , the CO in the gases passing through the cells e having about the same thermal conductivity as air and other constituents, aside from CO_2 , of ordinary furnace gases. It will be understood that in the Wheatstone bridges shown in Fig. 9, the same general operation would follow, if one resistance R and one resistance r of each bridge were replaced by fixed resistance arms. The use of two resistances R and two resistances r , as shown, makes it unnecessary to provide fixed bridge resistance arms, while adding to the sensitivity and range of the bridge indications.

The apparatus disclosed possesses numerous important practical advantages. An advantage of the cell block and resistor mounting structure illustrated is the ready feasibility of incorporating more than one pair of comparison cells in a single metallic block or body, since each cell block can be made large enough to incorporate as many cells as may be required and the different resistors are insulated from the cell block. In practice, the electrical determination of gas composition, based on the thermal conductivity of the gas, requires a comparison of effects due to the different thermal conductivities of the test gas and of a standard gas as the electrical quantities measured differ so slightly as to make absolute measurements based on the test gas alone uncertain and unreliable.

The accuracy of comparison cell measurements depends, of course, upon the practical elimination of all temperature differences between the cells compared except the differences which result from the different thermal conductivities of the gases in the cells.

Furthermore, it is highly desirable to eliminate appreciable inequalities in the hu-

midity or water vapor content of the gases compared, since such inequalities tend directly to errors in the measurements made, the possible error being greater at higher temperature. With the device C described, the flue or other test gas is reduced to a temperature definitely related to the temperature of the cell block. In passing through the cleaning and cooling passages D^3 , D^4 , and D^5 , the test gas is ordinarily cooled to a few degrees below the temperature of the cell block, since the latter receives heat from the resistances e and ea , and the dissipation of this heat is too slow to prevent the cell block from being a few degrees warmer than the housing body. The temperature equalization of the cell block and body is impeded by the joint resistance to heat transfer from the portion of the cell block head E' clamped against the top of the housing body D, particularly as a non-metallic gasket is ordinarily interposed between the head and body.

The test gas in passing through the channels D^3 , D^4 , and D^5 is ordinarily cooled to or below its saturation temperature. The filter provisions prevent entrained moisture from being carried into the cells, and even if some minute quantity of free moisture did enter the cells with the test gas, the increased temperature imparted to the gas in the cell block insures the evaporation of this moisture, as with its increased temperature the gas is then slightly under-saturated. In consequence the cell walls are kept clean, and the difference between the humidity of the test gas and of the saturated air or other standard gas sealed in the cells ea and chamber e' is so slight as to be inconsequential from a practical standpoint. The method of compensating for the humidity of a test gas by maintaining it and the standard gas each in a practically saturated condition has not heretofore been accurate in practical gas analysis apparatus, because of the inability in such prior apparatus to maintain the approximately uniform temperature conditions secured with the present invention.

It will be apparent that the gas comparison devices C and CA disclosed tend to equalize the temperature of the gases compared, by reason of the formation of the cells in a unitary metallic cell block, and the enclosure of the latter in a unitary metallic housing body, so that the use of the cooling water in the passages D^2 is not always essential. The use of cooling water as described, however, prevents the test gas from entering the comparison cells much under-saturated, as it might if the gas were preliminarily cooled in the piping conveying the gas to the comparison cell structure, to a temperature appreciably below the cell block temperature. While the accuracy of

the measurements obtained do not directly depend upon the cell block temperature, it is generally desirable to have the cell block temperature comparatively low because the 5 water vapor content of a saturated gas increases rapidly as the gas rises in temperature above ordinary atmospheric temperatures, and the higher the saturation moisture content of the gas, the more difficult is it 10 to make accurate compensation therefor.

Water of condensation formed in the apparatus may be continuously withdrawn as formed, by suitable trap arrangements, or it may be periodically removed by opening 15 the passages D^3 , D^4 and D^5 at their lower ends as is readily possible with the construction illustrated. The quantity of condensate collecting in the apparatus in any one period of use is ordinarily quite small, 20 and all or practically all of this condensate will collect in the lower end of the chamber D^3 . In practice I consider it desirable in some cases to maintain a body of condensate in the lower end of the passage D^3 , 25 and to place water in the bottom of that channel when the apparatus is initially put into operation, so that the entering gas will bubble through the water. This not only neutralizes the effect of transitory variations 30 in the temperature of the entering gas but is primarily important because it insures full saturation at all times of the gas flowing upward through the channel D^3 .

In the comparison cell device CA, the 35 gas passing to the chamber e' and cells ea through the pipe B' , will ordinarily reach the cells at practically the temperature at which it leaves the device C, and hence at about the same temperature at which the 40 gas coming to the device CA through the pipe B^2 enters the cells e of that device. In consequence it is not ordinarily necessary to pass the gas supplied by the pipe B' through cooling channels in the body D of the device 45 CA, though this may readily be provided for whenever necessary or desirable, as it involves nothing more than the formation of an extra gas passage or passages in the body D, and in the head of the cell block E 50 of the device CA.

The mechanical structure of the devices C and CA is obviously simple and desirable for reasons already explained. Furthermore, the fact that the gas cells are formed 55 in a cell block separable from the body of each comparison cell structure, makes it possible to do rough mounting work, including the attachment of all pipe connections to each such body before the corresponding 60 cell block is put into place, and thus eliminates a source of injury by mechanical shock to the resistance filaments which are relatively delicate and easy to injure.

The fact that each of the resistors R and 65 r is helical in form, and is connected at its

opposite ends to rigid conductors O and P, both mounted in the same insulation plug M in which the conductor O is axially adjustable, is an important characteristic of the apparatus since this permits of a variation 70 of the temperature and thereby the resistance attained by the resistor under any given conditions of operation. This follows from the fact that the rate at which the resistor dissipates heat is increased, other things being equal, by spreading the resistor convolutions farther apart, and is diminished by bringing them closer together. This feature of the invention makes it readily possible to accurately calibrate the apparatus by first making the various resistors of the proper lengths to have equal resistances when carrying currents too small to produce appreciable heating, and then, after the cold resistances of the resistors are thus 75 equalized, spacing the convolutions of the different resistors to equalize their resistances when the resistors are heated by a current large enough to produce an appreciable heating effect and are exposed to the same 80 cooling conditions.

The resistor arrangement disclosed offers an easy method of obtaining a condition which has heretofore been impracticable to obtain; namely, of having the bridge in 85 balance when the test gas cells e contain gas of normal or average composition, as for example furnace gases containing 14% of CO_2 , while the comparison cells ea contain a convenient gas such as air. In this case 90 the convolutions of resistors R may be spaced farther apart, or be wound with a larger diameter, to increase the cooling effect of the gas of relatively low thermal conductivity contained in cells e . Since the 95 distance between the resistor convolutions may be adjusted while the apparatus is in, or in condition for operation, the necessary adjustment may readily be made with each individual instrument, which is evidently 100 impossible if different sizes of resistor wires are used for resistors R and r , or if different diameters are used for cells e and ea as have heretofore been suggested. The 105 method just described is superior also to the 110 method of balancing the bridge when using unlike gases in cells e and ea by adjustment of the slide wire S, because when the slide wire is placed in a position other than that which balances the bridge when the resistors 115 are unheated, the meter reading will change when the bridge current varies slightly when "normal" gas is in cells e . When balanced with normal gas no error is produced at 120 this reading by the galvanometer temperature coefficient.

The disclosed mode of mounting the resistors in the cell blocks avoids all necessity for grounding the resistors to the cell block, and thus permits two or more resistors 130

tors R and two or more resistors r to be mounted in a single cell block, and to be connected in a single Wheatstone bridge as shown in Fig. 9, which is not possible when one end of each resistor is grounded by contact with the cell block, as has heretofore been the usual practice.

The formation of the cell blocks E of cast aluminum is of advantage because cast aluminum is not corroded by gases which will corrode iron or brass, which have heretofore ordinarily been employed, and in many cases have been gold-plated to avoid corrosion troubles. Where trouble is anticipated from gas diffusion through the pores of the aluminum, the cell block may be dipped in molten cannauba wax, or beeswax, or varnish, and the wax or varnish bath then subjected first to vacuum and then to pressure, whereby the cell block pores are filled. The wax hardens as soon as the casting is removed and cooled, and the varnish impregnated casting may be air-dried or baked to oxidize and harden the varnish. Treated with either material, the cell block is gas tight, and the cell walls and channels are coated with a material highly resistant to the corrosive action of gases in contact therewith.

Instead of making the cell walls of aluminum, they may well be made in some cases of lead, as in the construction shown in Figs. 7 and 8, wherein the cell block EA, while it may otherwise be identical in form with the cell block previously described, has its body portion composed of a shell E¹⁰ cast integral with the head of the cell block, and surrounding a lead core E¹¹ cast in place therein. The cells e and ea, and the chamber e', may be drilled in the core E¹¹, or may be formed by the use of suitable core patterns when the lead core E¹¹ is cast. The use of lead as a cell wall material is advantageous because lead is not sufficiently porous to permit objectionable gas diffusion through the cell walls, and because lead is not corroded by sulphur compounds or other constituents of, furnace gases which have a corrosive action on such metals as iron, copper or brass. Corrosion of a cell wall is to be avoided if for no other reason than because it modifies the rate of heat transfer between the cell wall and the enclosed resistor.

The cell block EA may be identical in contour and in the arrangement of its cells, chambers and passages with the cell block E so that that it is adapted for interchangeable use with the cell block E in the same housing body D. In Figs. 7 and 8, however, the housing body DA does not include gas filtering provisions, but does include a water jacket space D¹⁰, which surrounds the cell block cavity D', and to which cooling water inlet and outlet pipes L' and L² are

connected. The housing body DA is formed with cooling gas passages D¹¹ and D¹², through one of which gas may be passed to the cells e, while the other is sealed or is used to pass gas to the cells ea of the cell block EA, as conditions make desirable.

Certain novel features of the invention disclosed but not claimed herein are claimed in my copending application Serial No. 68,650, filed November 12, 1925, of which in certain respects this application is to be regarded as a continuation.

While in accordance with the provisions of the statutes I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent is:

1. Gas analysis apparatus comprising gas cells and electrical resistance members therein, and an enclosing metallic structure formed with a gas cleaning and cooling space, gas cleaning provisions therein and connections for passing gas through said space into one of said cells.

2. Gas analysis apparatus comprising a cell block formed with gas cells, gas heating resistances in said cells and a metallic structure surrounding said cell block and in relatively poor heat conductive relation therewith, said structure being formed with a gas passage communicating with, and supplying gas to one of said cells.

3. Gas analysis apparatus comprising a cell block formed with gas cells, gas heating resistances in said cells, and a metallic structure surrounding said cell block and in relatively poor heat conductive relation with the latter, said structure being formed with a gas passage communicating with, and supplying gas to, one of said cells, and with a water cooling passage.

4. In determining the thermal conductivity of a gas, the method which consists in cooling the gas to a temperature as low as its saturation temperature, removing entrained moisture, slightly increasing the temperature of the gas and then comparing the thermal conductivity of the gas with that of a saturated gas at approximately the same temperature.

5. A comparison cell device for measuring the thermal conductivity of a gas which comprises gas cells, an enclosing metallic structure formed with gas cooling and clean-

ing passages, and gas cleaning provisions therein.

6. Apparatus for furnace gas analysis comprising cells and resistors for determining the CO_2 content of the gas, cells and resistors for determining the CO content of the gas, a meter, said meter comprising a scale having a zero point and a pointer adapted to swing in either direction from said zero point and means for connecting it alternately to the resistors for CO_2 determination and to the resistors for CO determination, said means being so relatively arranged that the pointer will swing in one direction from said zero point when connected to one set of resistors and will swing in the opposite direction from said zero point when connected to the other set of said resistors.

7. In determining the thermal conductivity of a gas, the method which consists in initially adding moisture to the gas as required to saturate the latter, then removing entrained moisture from the gas, and slightly increasing the temperature of the gas, and then comparing the thermal conductivity of the gas with that of a saturated gas at approximately the same temperature.

8. In apparatus for determining the thermal conductivity of a gas, the combination of a cell structure comprising a body member of aluminum formed with a gas receiving cell chamber, a resistor therein formed of material varying in electrical conductivity as its temperature varies, means for passing an electric heating current through said resistor, and means responsive to the voltage drop in said resistor.

9. Apparatus for gas analysis comprising cells and resistors for determining the CO_2 content of the gas, cells and resistors for determining the CO content of the gas, a meter, and means for connecting it alternately to the resistors for CO_2 determination and to the resistors for CO determination.

10. In apparatus for gas analysis, the combination of a thermal conductivity device comprising cells and resistors for creating an electrical force which is a measure of the initial CO_2 content of a gas, means for converting the CO content of gas into CO_2 , a second thermal conductivity device comprising cells and resistors for creating an electric force which is a measure of the difference in CO_2 contents of the gas in its initial condition and after the initial CO content has been converted into CO_2 , and a meter for alternately measuring said electrical forces.

11. In apparatus for gas analysis, the combination of a thermal conductivity device comprising a standard cell and a test gas cell and a resistor in each of said cells, means for converting the CO content of gas into CO_2 , a second thermal conductivity device

comprising two test cells and a resistor in each of said cells, means for passing some of the gas to be tested in series through the test cell of the first mentioned device and through one of the test cells of the second mentioned device, means for passing some of the gas to be tested in series through said CO converting means and through the second test cell of said second mentioned device, an electric meter, and means for connecting it alternately to the resistors of the first mentioned device and to the resistors of the second mentioned device.

12. Apparatus for gas analysis comprising in combination a thermal conductivity device comprising comparison cells and resistors therein, a second thermal conductivity device comprising comparison cells and resistors therein, means for converting the CO content of gas into CO_2 , means for passing gas through the last mentioned means and thence through one of the cells of said second device, means for passing gas through a cell of the first device and thence through a second cell in the second device, means associated with each of said devices for conditioning gas entering the cells thereof, and electrical measuring means associated with said resistors.

Signed at Philadelphia, in the county of Philadelphia, and State of Pennsylvania, this 17th day of August, A. D. 1926.
